United States Patent Office.

GARRETTSON SMITH AND HENRY BROWN, OF PHILADELPHIA, PENNSYLVANIA,
ASSIGNORS TO ABBOTT AND NOBLE, OF SAME PLACE.

Design No. 3,590, dated July 27, 1869; antedated June 29, 1869.

DESIGN FOR THE PLATES OF A STOVE.

The Schedule referred to in these Letters Patent and making part of the same.

To all whom it may concern:

Be it known that we, GARRETTSON SMITH and HENRY BROWN, of Philadelphia, county of Philadelphia, State of Pennsylvania, have originated a new Design for the Plates of a Stove; and we do hereby declare that the accompanying drawing, and following explanation thereof, form a full, clear, and exact description of the said design.

In the drawing, the figure represents in perspective the plates of our stove, the base, A, of which consists of the bottom plate *b*, two opposite side plates *c c*, (the ornamentation of the latter being clearly shown in the drawing,) and the front plate *d*, the latter having the two ornamental doors shown, and the base being supported on suitable legs *a a*.

The cylinder of the stove is surrounded with a lat-

tice-work casing, B, in front of which is the fire-door G, the casing being surmounted with a plate, H.

The top plate of the stove consists of the circular plate I, ornamented as shown, and surmounted with an urn, the design of which will be too clearly understood, by reference to the drawing, to need description.

We claim the design for the plates of a stove, substantially as described, and as represented in and by the accompanying drawing.

In testimony whereof, we have signed our names to this specification, in the presence of two subscribing witnesses.

GARRETTSON SMITH.

Witnesses: HENRY BROWN.
